Fig. 5

The diagram illustrates a complex electrical circuit, likely a safety device for a steam boiler. Key components include:

- Top Left:** A valve assembly with a handle labeled **45b** and a body labeled **42a**. A rod connects the handle to a lever system.
- Top Right:** A valve assembly with a handle labeled **46** and a body labeled **42b**.
- Central Column:** A vertical column labeled **t** at the top, containing a resistor labeled **R**, a solenoid with a plunger, and a switch labeled **A**.
- Right Side:** A vertical column labeled **B** at the top, containing a switch and a solenoid with a plunger.
- Bottom Left:** A vertical column labeled **C** at the top, containing a switch and a solenoid with a plunger.
- Bottom Right:** A vertical column labeled **Fig. 6** at the top, containing a switch and a solenoid with a plunger.
- Bottom Center:** A signature that reads Rudolf Max Braun and Inventor.

Inventor

UNITED STATES PATENT OFFICE

RUDOLF MAX BRAUN, OF VIENNA, AUSTRIA

CALL-ANSWERING DEVICE FOR TELEPHONE STATIONS

Application filed March 9, 1931, Serial No. 521,275, and in Austria March 17, 1931.

My invention relates to a device which may be built in or connected to a telephone station, particularly a subscriber set, and which gives, if in the working position, to anybody ringing up this station a clearly audible signal. This signal indicates that the call has reached the station and therefore, that line and apparatus are working and may also be used to announce a certain fact, for instance

10 the temporary absence of the subscriber.

My invention is particularly useful on temporary lines or on lines which are frequently interrupted, such as military field-lines and allows an instant testing even in the case that

15 the operator of the called station is absent. My invention may also be used in cities in connection with a special office for the acceptance and deliverance of messages for absent subscribers. In this case, the audible signal not

20 only announces to the caller the fact that the called subscriber is absent but also that a message for the same will be received at and forwarded by the above mentioned office.

It is one of the objects of my invention to

25 provide a device of the kind described with a visible indicator showing to the called subscriber as he returns to his set that he has been called during his absence.

The main object of my invention is to pro-

20 vide a simple, inexpensive device for the pur-

pose specified above, which may be used in

connection with any existing telephone sys-

tem, such as local battery (magneto), central

battery, machine-switching, and also on two-

35 and four-party lines with selective ringing (A. C. with superimposed D. C.) as well as in connection with private branch extensions and residence-systems without any alteration of the system. The device according to my

40 invention has only very few moving parts, and requires neither spring motors nor bat-

teries or other auxiliary sources of current

and does not draw any current from the cen-

tral battery in the telephone exchange. An-

45 other object of my invention is to provide a call-answering device which in no case is liable to interfere with the working or opera-

tion of the central office equipment.

My invention also aims to provide a call-

answering device which gives an audible sig-

nal after the ringing current has been shut off, that is with practically all the existing telephone-systems, between the successive ringing periods. The signal produced by the device according to my invention is distinctly

55

different from and is not liable to be con-

founded with any other sound used at present

with telephone-systems, such as the busy-sign,

the ringing sound or the dial-tone.

My invention also provides a switching de-

60

vice which enables the subscriber to make the device at will operative or inoperative and alternatively to provide for audible signals of

several different characters.

The principle on which all the different

65

embodiments of the invention are based is the use of a member capable to oscillate or vi-

brate freely mechanically which is set in motion by the incoming ringing current by di-

rect action of an electromagnetic device en-

70

ergized by said current. Said member keeps

on oscillating for some time (by virtue of its

momentum) after the ringing current has

been shut off and these free oscillations are

used to effect the signaling. After a number

75

of oscillations the said member comes to a

rest because of the damping by friction, air-

resistance or the like. The member capable

to oscillate may consist of a pendulum, of a

80

weighted spring, of a watch-movement or of

any other element capable of slow mechanic

oscillations. Alternatively an element may

be used which is able to vibrate with an audi-

ble frequency, such as a tuned fork, bell or

85

gong. Broadly spoken, any element having

85

momentum and being influenced by a direc-

tional force may be used. Said member may

be set in motion by moving it away from its

neutral position by the electro-magnet ener-

90

gized by the ringing current or by a hammer

actuated by said electro-magnet which strikes

the element capable of mechanic oscillations.

The return-signal to the calling subscriber

95

may be produced by making and breaking

contacts periodically as the pendulum or the

95

like swings or by varying the magnetic flux

in coils connected to the line and arranged

in the field of a permanent magnet, as the

tuned fork or the like vibrates in front of the

100

poles of said magnet. If contacts are used,

they may close and open a local primary circuit or they may effect the charging and discharging of a condenser. It is one important feature of my invention that the oscillating element is set in motion by the direct action of the electro-magnet energized by the incoming ringing current without interposing any complicated mechanism. Thus, a simple, effective and trouble-proof way is provided to store the power of the incoming ringing current and to use this power for the transmission of the return-signal after the end of the ringing period.

Other advantages and features of my invention will become clear from the following description with reference to the drawing, in which:

Fig. 1 is the diagram of a device according to the invention for the use with magneto-stations with local primary battery.

Fig. 2 shows also a device for magneto stations which is adapted to give two different signals.

Fig. 3 shows a device for use with central-battery-stations or in machine switching areas provided with a drop.

Fig. 4 shows a device similar to Fig. 3 adapted to give two different signals.

Fig. 5 is the diagram of a device using a tuned fork and a telephone transmitter.

Fig. 6 is the diagram of a device as shown in Fig. 3 connected to a four party station through a rectifier.

In the example shown in Fig. 1 of the drawing, 1 is a pendulum provided with an iron bar or armature 2, said armature being arranged in front of the polepieces of an electro-magnet 3. This electro-magnet is provided with two coils 3a and 3b. The coil 3a has a high resistance (say 2000 ohms) and is connected via a switch 4 to terminals 5a and 5b bridged across the telephone line or connected to the instrument in the same way as the usual auxiliary ringer. The coil 3b is connected in a local circuit including the battery 7, which may be the local primary battery of the magneto-set, and the contact 6 mounted on the spring 6a of very high resiliency.

If ringing current comes in over the line and the terminals 5a and 5b and passes through the coil 3a, the electro-magnet 3 is energized and attracts the armature 2, thus bringing the pendulum 1 out of its neutral position. As the ringing current ceases, the pendulum swings back and oscillates for some time, each oscillation closing the contact 6. The making and breaking of the contact 6 causes induction-impulses in the coil 3a acting as a secondary coil which impulses are sent into the line and are audible to the calling subscriber on the other end of the line. The sound produced is similar to the ticking of a watch and is very clearly audible in the receiver.

Fig. 2 shows a similar device which is adapted to give two different signals i. e. a ticking sound of the same or of twice the frequency of the oscillations of the pendulum. This example shows the use of a condenser 19 of about 2 micro-farad between the line-terminals 15a and 15b and the coil 13a energizing the electro-magnet 13. The pendulum 11 is in this case a spring or a strip of resilient metal bearing on one end the armature 12. The local primary circuit includes the battery 17, the coil 13b and, according to the position of the switch 14; one or both of the contacts 16 and 18 mounted on resilient blades 16a and 18a, respectively.

If only one contact is connected into the circuit, the ticking is slow, if both contacts are used the ticking is more rapid.

Fig. 3 shows a similar device for use on central-battery or machine-switching lines provided with a drop to announce the fact that a call has been received. The pendulum 21 is similar to that of Fig. 2 except that the air-gap between the electro-magnet 23 and the armature 22 is inclined to the axis of the iron-core in order to insure the magnetic action over a greater distance. The energizing coil 23a is connected over a condenser 29a and a switch 24 to the line-terminals 25a and 25b. The pendulum 21 is connected to one terminal and the contact 26 mounted on the arm 26a to the other terminal over a condenser 29b. A drop 32 is provided and normally held in the raised position by a dog 31a on the end of a bell-crank lever 31 pivoted at 31b.

If the electro-magnet 23 is energized by the incoming ringing-current, the pendulum 21 and the armature 22 moves in the position shown in dotted lines. The bell-crank lever 31 is angularly displaced by the armature 22, the dog 31a is raised and releases the drop 32, which falls down in the position shown in dotted lines.

If now the ringing current is shut off and a D. C. voltage is applied to the line, as usual with all C. B. and machine-switching telephone systems the pendulum 21 is released and oscillates. The condenser 29b is charged every time as the pendulum 21 touches the contact 26 mounted on the resilient blade or arm 26a. This inrush of charging current—although by far too weak and too short to actuate the line relay in the telephone exchange—is clearly audible in the receiver of the calling station. To discharge the condenser 29b while the pendulum 21 swings back, i. e. away from the contact 26, a high resistance in the order of several hundred thousand ohms may be shunted across the signaling condenser 29b.

Another way of discharging the signaling condenser which makes it possible to utilize the discharge current for signaling is shown

in Fig. 4. This figure also illustrates the use of a watch movement in the place of a pendulum and the use of an individual electro-magnet for the drop. This drop is of conventional design and comprises a drop plate 52 held by a bell-crank-lever 51 pivoted at 51b and an electro-magnet 43 with two coils 43a and 43b, the coil 43a being connected in series with the condenser 49a, the coils 53 and the switch 44a across the line terminals 45a and 45b. In front of the pole-pieces of the electro-magnet-coils 53 an armature 42 is mounted on a rotatable shaft 42a and held in the position shown in full lines by a very resilient spiral spring (as used with watch movements) 42b. This spring also serves to connect the armature via a condenser 49b to the terminal 45a. A resilient contact arm 41 is fastened to the armature, contact springs 20 46 and 48 being provided on both sides of this contact-arm.

The spring 46 is connected to the line terminal 45b, the other spring 48 may be connected, by means of the switch 44b either via 25 a resistance 50b or through the coil 43b and resistance 50a to terminal 45a.

An incoming ringing current causes the drop 52 to fall and also energizes the coils 53. The armature and the contact arm 41 swings to the position shown in dot and dash lines. If now the ringing current is shut off and D. C. is imposed on the line from the central-office, the armature swings back and forth for some time and touches alternatively 35 the contact springs 46 and 48. If the arm 41 touches the spring 46, the signaling condenser 49b is bridged across the line and charged. If the arm 41 swings back and makes contact with the spring 48, the condenser 49b is discharged either directly over 40 the resistance 50b (to avoid sparking) or through coil 43b and resistance 50a, according to the position of the switch 44b. Thus, it is possible to provide for two different signals 45 consisting of a ticking sound of lower or higher speed, similar as with the device illustrated in Fig. 2.

When using the call-answering device with four-party stations it is necessary that the 50 electro-magnet which actuates the vibrating element is responsive only to impulses of one predetermined direction. For this purpose, a polarized armature 62 with a biasing spring 61 may be used as shown in Fig. 5. This 55 armature 62 is influenced by an electro-magnet 63 and a polarizing permanent magnet 64. The winding of this electro-magnet is connected to the terminals 65a and 65 which are connected into the circuit of the subscriber set in the same manner as an auxiliary ringer. Alternatively the electro-magnet 63 may replace the ringer of the station.

A hammer 62 is connected to the armature 62 and strikes, if the electro-magnet 63 is excited with A. C. and super-imposed D. C.

of a certain polarity, the tuned fork or gong 66 which vibrates at an audible frequency. The vibrations of the tuned fork or gong cause a periodical change of the magnetic flux of the permanent magnet 68 through the coils 57. The induction current such as generated in the coils 67 is transmitted via a condenser 69 to the terminals 65c and 65d bridged across the line. The effect is that the calling subscriber hears a musical tone in his receiver.

This type of call-answering device may be used, of course, also on individual line stations.

A way of using the call-answering device as shown in one of the Figures 1-4 on four party lines with selective ringing is illustrated in Fig. 6. In this figure A designates the well-known wiring diagram of a subscriber set (party on tip). The call-answering device B is connected to the ringer R of the set via a rectifier C, preferably of the dry metallic type, which allows only the positive impulses to pass.

My invention is, of course, not limited to the examples shown, any combination of the different features shown in the figures of the drawing being within the scope of the invention. The electro-magnet may be of any suitable form, such as the usual horseshoe type with double coils, or of the barrel-type as commonly used for telephone-relays. The oscillating element may be a suspended or inverted pendulum or of the watch movement type as shown, a swinging column of a liquid enclosed in a U-shaped tube may also be employed. Alternatively a rotatable element may be used, which keeps on turning for some time after the ringing element has been shut off.

What I claim is:—

1. In a call-answering device for telephone-stations, the combination with an electro-magnetic device actuated by the incoming ringing current, of an element adapted to oscillate freely by virtue of its momentum after being set in motion by said electro-magnetic device, and means for converting said free oscillations into electric impulses in a line.

2. In a call-answering device for telephone-stations, the combination with an electro-magnet energized by the incoming ringing current, of a pendulum bearing an iron armature arranged in front of the poles of said electro-magnet and adapted to be brought away from its neutral position if said electro-magnet is energized, contacts arranged in the swinging path of said pendulum and means for converting the making and breaking of said contacts into electric impulses in a line.

3. In a call-answering device for telephone-stations, the combination with an electro-magnetic device actuated by the incoming ringing current, of an element adapted to oscillate freely by virtue of its momentum

after being set in motion by said electro-magnetic device, contacts arranged on both sides in the swinging path of said element, a switch to make operative or inoperative one or both of said contacts, and means for converting the making and breaking of said contacts into electric impulses in the line.

4. In a call-answering device for telephone-stations, the combination with an electro-magnetic device actuated by the incoming ringing current, of an element adapted to oscillate freely by virtue of its momentum after being set in motion by said electro-magnetic device, contacts arranged in the swinging path of said element and a condenser connected to the line by said contacts.

5. In a call-answering device for telephone-stations, the combination with an electro-magnetic device actuated by the incoming ringing current, of an element adapted to oscillate freely by virtue of its momentum after being set in motion by said electro-magnetic device, contacts arranged in the swinging path of said element and a condenser shunted by a high resistance connected to the line by said contacts.

6. In a call-answering device for telephone-stations, the combination with an electro-magnetic device actuated by the incoming ringing current and including a hammer, of an element adapted to oscillate freely at an audible frequency by virtue of its momentum after being struck by said hammer, and means for converting the free oscillations of said element into electric impulses in the line.

7. In a call-answering device for telephone-stations, the combination with an electro-magnetic device actuated by the incoming ringing current and including a hammer, of a tuned fork adapted to oscillate freely at an audible frequency by virtue of its momentum after being struck by said hammer, and a permanent magnet arranged with its poles adjacent to said tuned fork and provided with windings connected to the line.

8. In a call answering device for telephone-stations, the combination with an electro-magnetic device actuated by the incoming ringing current and connected to the line via a rectifier, of an element adapted to oscillate freely by virtue of its momentum after being set in motion by said electro-magnetic device, and means for converting said free oscillations into electric impulses in the line.

In testimony whereof I affix my signature.
RUDOLF MAX BRAUN.
